UNITED STATES PATENT OFFICE.

WILLIAM H. DUNHAM, OF HOKAH, MINNESOTA, AND JAMES WIDNEY, OF ALLEGHENY, ASSIGNORS OF PART INTEREST TO SAMUEL P. ROSS, OF PITTSBURG, PENNSYLVANIA.

IMPROVEMENT IN CAR-BRAKE SHOES.

Specification forming part of Letters Patent No. 71,591, dated December 3, 1867; reissue No. 4,466, dated July 11, 1871.

DIVISION B.

To all whom it may concern:

Be it known that we, WILLIAM H. DUNHAM and JAMES WIDNEY, the former now of Hokah, State of Minnesota, the latter of the city of Allegheny and State of Pennsylvania, have invented a certain Improvement in Car-Brakes; and having assigned a portion of our interest in the same to SAMUEL P. ROSS, of the city of Pittsburg and State of Pennsylvania aforesaid, the following is a specification:

The invention consists in a new and improved brake-head and brake-shoe, to be attached to locomotives and car-trucks, the novelty and utility of which are in the mode of fastening them together by means of a hook and a lug on the brake-shoe fitting into slots or apertures in the brake-head, thereby firmly holding them together and greatly facilitating the removal of worn-out brake-shoes and the replacing of new ones.

The accompanying drawing represents the machine in separate parts and when put together. Figure 1 is a side view of the brake-head. Fig. 2 is a side view of the brake-shoe. Fig. 3 is a side view of the brake-head and brake-shoe fastened together. Fig. 4 is a back view of the brake-head. Fig. 5 is a front view of the same. Fig. 6 is a back view of the brake-shoe.

A represents a casting, usually called a "brake-head," curved on its face to suit the curvature of the car-wheel. Upon the back of the brake-head are placed two transverse flanges, y y', for the purpose of holding between them firmly the brake-beam. Reaching from the flange y to the

upper end of the brake-head are two other flanges running lengthwise, with a hole, n, in them, through which, by means of a stirrup, the brake-head and brake-beam are suspended from the car-truck. Running transversely to the curved face of the brake-head A are jogs or ribs q q q', for the purpose of keeping the brake-head A and the brake-shoe B apart, forming air-spaces, and thereby preventing heating. The brake-shoe B is also a casting, conforming in length, width, and curvature to the brake-head A, and of whatever thickness may be deemed proper. It has at the upper end the hook F and at the lower end the lug G, which last is furnished with the key-slot O. The hook F is made to drop into the slot S in the upper end of the brake-head A, and the lug G is made to pass through the slot E in the lower end of the same. A key passed through the key-slot O secures the whole together.

We claim—

The brake-shoe B, formed with the hook F and the lug G, the hook having a bearing in the slot S on the upper end of the brake-head, and the lug passing through the slot E in the lower end of the same and secured by a key, all constructed and arranged substantially as and for the purpose set forth.

JAMES WIDNEY.

S. P. ROSS.
